Francis V. Noette

UNITED STATES PATENT OFFICE.

FRANCIS V. NOETTE, OF BROOKLYN, NEW YORK.

IMPROVEMENT IN UMBRELLAS.

Specification forming part of Letters Patent No. 43,788, dated August 9, 1864.

To all whom it may concern:

Be it known that I, FRANCIS V. NOETTE, of Brooklyn, in the county of Kings, in the State of New York, have invented a certain new and useful Improvement in the Construction of the Frames of Umbrellas and the like Structures; and I do hereby declare that the following is a full and exact description thereof.

My improvement relates to the part where the spreading ribs and stretchers or braces are joined to the main standard; and it consists in the use of sockets, cheaply formed, of thin tubing in two parts, one within the other, within one end of each spread, and properly shaped to confine the ends of the ribs or stretchers between them, in the manner to be hereinafter described.

The accompanying drawings form a part of this specification.

Figure 1 is a side view; Fig. 2, a top view; Fig. 3, a central vertical section; Fig. 4, a cross-section on the line S S in Fig. 3; Fig. 5 a cross-section on the line T T in Fig. 3; Figs. 6, 7, and 8, different forms of the ends of the ribs and stretchers, either of which form of ends may be used with my invention. Fig. 9 is a vertical section on a larger scale, showing two modes of putting together the parts, either of which modes may be used with my invention.

Similar letters of reference indicate like parts in all the figures.

My invention is applicable to umbrellas of all kinds, parasols of all kinds, and all the varieties of sunshades and analogous articles of whatever name, as also to any kind of tent or other structure which may require a frame adapted to fold in a similar manner.

The purpose of my invention is to cheapen the construction and facilitate repairs, and to produce a stronger and more durable structure than that made in the ordinary manner.

To enable others skilled in the art to make and use my invention, I will proceed to describe its construction and operation by the aid of drawings and of the letters of reference marked thereon.

A is central staff or handle of the umbrella.

B B, &c., are the ribs or arms, which are to be folded and extended; and C C, &c., are the stretchers or braces by which the ribs B are operated. These parts are constructed in the

ordinary manner, except that the ends of the ribs B and stretchers C, which are hinged to the standard A, are formed as shown in one of the Figs. 6, 7, and 8, or in some analogous manner, so as to present a large part or head at that end.

D and E are half-sockets, adapted to embrace and retain the heads of the arms or stretchers, allowing the latter to turn freely, but not to escape, when the parts D and E are secured together. When the parts D and E are separated, the heads of the ribs B and stretchers C may be easily removed and replaced to admit of repairs. Each of these half-sockets is formed of a short length of sheet brass or copper tube. The tube may be made of sheet metal by bending it around and brazing the edges together, so as to form a tube; or it may be made by any of the processes for producing tubes from ingots, so as to possess a uniform thickness and character throughout. The tube D is originally of such diameter as to fit closely around the standard A. The tube F is originally larger. The ends both of D and E, which are to receive the heads of the ribs or stretchers, are expanded and formed in the shape represented by spinning it in a lathe, or striking up in dies or otherwise, either at a single operation, or by several steps, properly annealing it between each operation, so that when the parts D and E are properly fitted together, a semicircular groove, d, in one shall match against a corresponding semicircular groove, e, in the other to form hollow ring adapted to hold the heads b or c, and allow them to turn. (See Fig. 9.) Portions of the end of the inner tube, D, are then cut out by suitable tools, so as to form mortises d, (see Fig. 1,) in each of which mortises the neck of a rib or stretcher may turn while its head is retained in the cavity formed by the grooves d and e, all of which will be understood with little difficulty from the drawings. The full lines show the position of the ribs and stretchers when the umbrella is open or extended. The dotted lines show their position when the umbrella is closed. The device D and E, used at the upper end of the standard to hold the ribs B, is placed inverted relatively to the corresponding device used to hold the stretchers C e, for obvious reasons. The lowermost is made longer, and should fit easily

thereon, and be conveniently operated, and held in the ordinary manner. The transverse pin G passes through holes in both the tubes D and E at the upper end of the standard A, and holds them tightly together or releases them, to allow the contained arms B b to be removed and inserted. A male screw-thread on the tube D and a female screw-thread on the tube E perform a corresponding function for the lower device, to allow the contained stretchers C c to be held and released.

To fit my device when made in the lowermost or screw form, I seize the outer tube, E, with a pipe-wrench or analogous tool, and turn it around upon the inner tube, D. In the lower end of Fig. 9 the parts are represented as so constructed and widely separated.

Additional tubes may be brazed or otherwise fitted upon either of the tubes D or E at

any point to thicken them. In Fig. 3 the lowermost edge of the inner tube, D, is represented as thus thickened to form a bead, and the screwed portion above is represented as correspondingly thickened.

Having now fully described my invention, what I claim as new therein, and desire to secure by Letters Patent, is as follows:

In the construction of umbrellas and analogous folding structures, the employment of metal sockets D and E, formed from tubes, as described, and adapted to confine and release the folding parts of the frame work, substantially in the manner and for the purpose herein set forth.

FRANCIS V. NOETTE.
